UNITED STATES PATENT OFFICE.

FRANK H. ROGERS, OF PHILADELPHIA, PENNSYLVANIA, ASSIGNOR TO WILLIAM CRAMP & SONS SHIP AND ENGINE BUILDING COMPANY, A CORPORATION OF PENNSYLVANIA.

GOVERNOR.

Application filed February 21, 1922. Serial No. 538,390.

To all whom it may concern:

Be it known that I, FRANK H. ROGERS, a citizen of the United States, residing at Philadelphia, in the county of Philadelphia and State of Pennsylvania, have invented certain new and useful Improvements in Governors, of which the following is a specification.

This invention relates to governors and particularly to a governor for regulating the speed of a hydraulic turbine. The chief object of the invention is to provide a governor which will regulate the flow according to the load in the most efficient manner and without causing overregulation or hunting and danger of water hammer due to sudden variations in the flow. A further object of the invention is to combine an automatic regulation and hand regulation together so that the shift from one to the other may be easily made at any instant without special preliminary adjustment of either regulation and without changing the position of the turbine gates or danger of losing control of the unit.

A further object of the invention is to provide a governor in which the various mechanisms will be gathered together and combined within a unitary structure supported from a single stand.

Further objects of the invention particularly in combining ruggedness and strength with simplicity of structure and in reducing to a minimum the number of adjustments to be made by the operator so as to simplify his duties in the plant will appear from the following description taken in connection with the accompanying drawings, in which

Fig. 1 is a sectional side elevation through a governor stand.

Fig. 2 is an end elevation of the same with parts shown in section.

Fig. 3 is a diagrammatic layout of the combined governor and hand control, and

Figs. 4 and 5 are sectional views of a special clutch device.

The governor consists primarily of a vertical shaft 1, the lower end of which is driven from the main turbine shaft either through belt and pulleys or by geared connection. This shaft rotates in a roller bearing 2 which acts as a combined steady and

thrust bearing. This bearing is supported in a sleeve 3, which in turn is secured to the upper part of the governor stand 4 supported on the base 31. The top of the shaft is directly connected to the governor head 5, which carries the two fly weights 6, so that these weights revolve with the shaft. 55 The centrifugal force due to motion is resisted by the springs 7, which are held in place between the weights and the rods 8. The weights 6 are connected through levers 9 and links 10, to the collar 11, so that the movements of the weights 6 in a horizontal plane produce corresponding movements of the collar 11 in a vertical plane. All of these parts however rotate with the shaft. 60

The vertical movements of collar 11 are 70 transmitted to the long floating lever 12, by means of a shoe connected to lever 12 near its center, and running in a groove in collar 11. One end of lever 12 is mounted to the pilot valve stem 13, and the opposite 75 end of lever 12 is connected at 14 to the short floating lever 15. The long floating lever 12 consists of two arms connected by cross bolts 16, so that the short floating lever 15 which consists of but a single arm, 80 may be located inside of the long lever. One end of the short lever 15, is connected through a link 17, to the piston rod 18 of the dash pot 19. The other end of the short lever 15, is connected through a link 20, to the cross head 21, which in turn is connected through a screw to the spring rod 22.

This rod 22 runs through the spring 23 which is contained within the casing 24. The washers 25 above and below the spring 90 23, permits vertical motions of the rod 22 by compressing the spring 23. The central portion of the short lever 15 is connected through link 26 to the restoring rod 27, which is in turn connected at the adjustable 95 point 28, to the restoring lever 29. Lever 29 rotates on shaft 30 supported in the governor base plate 31, and has a connection at 32 to the restoring shaft not shown which is connected to the operating cylinder shaft 100 which controls the turbine gates.

The pilot valve rod 13 is connected through ball and socket joint 33 to the pilot valve 34. This pilot valve operates inside of the main governor valve 35 in such 105 a way that the main governor valve 35 ex-

actly follows every motion of the pilot valve 34. This is accomplished in the following manner.

Fluid under pressure is admitted through 5 a pipe 136 to a central chamber 36, which is connected through drilled holes to the inner chamber 37. A movement of the pilot valve 34 in an upward direction admits pressure through the drilled hole 38, to the bottom 10 of the main valve 35, thus causing this valve to rise until the pressure supply from 37 is cut off. In order to permit the vertical motion of the main valve 35, the pressure above this valve is relieved through the 15 drilled hole 39, permitting the fluid to flow into chamber 40, and thence to chamber 41, and out through the exhaust pipe 140. Similar action occurs when the pilot valve 34 is lowered, resulting in a similar movement 20 in a downward direction of the main valve 35.

The arrangement of the parts of the said valve 35 causes the fluid under pressure from chamber 36 to flow into chamber 42 for 25 upward movements, so that this fluid will flow through chamber 43 to the pipe 44, which is connected to the closing side of the main operating cylinders connected to the turbine gates. At the same time, the upward 30 movement of the main valve 35 connects chamber 45 with exhaust chamber 41. As chamber 45 is connected to pipe 56 shown in Fig. 3, such a movement of the main governor valve permits the fluid to exhaust 35 from the opening side of the operating cylinder 69, and thus permits this cylinder to move in the proper direction to close the turbine gates. When the turbine unit is operating under normal conditions at a 40 steady load and normal speed, the position of the fly weights 6, is such that the pilot valve 34 is held in its central position, resulting in the main valve 35 being held in central position and hence cutting off all 45 flow of the fluid from the operating cylinders.

In case of a reduction in load on the turbine, the speed of the unit will start to increase, resulting in an outward movement of 50 the governor weights 6 and a corresponding vertical rise of the pilot valve 34 and the main valve 35. This movement, as explained will admit pressure from the governor system to the closing side of the main operating cylinder controlling the turbine gates. As the turbine gates close, the restoring connection from these gates attached to the lever 29, will cause an upward movement 55 of the restoring rod 27. This will result in an upward movement of the lever 15. Due to the resistance to motion of the dash pot 19, this end of the short lever 15 will be almost stationary, resulting in an upward movement 60 of the other end of the short lever by compressing spring 23, and

consequently an upward movement of the end of the long lever 12. As the long lever will pivot about its point of connection to collar 11, the upward movement of one end will result in a downward movement 70 of the other end and this movement will consequently tend to restore the pilot valve 34 to its original position and thus stop the movement of the turbine gates. However, due to the fact that the turbine is 75 producing more power than is being demanded by the generator, the speed continues to increase and the turbine gates continue to close, until the point is reached where there is a balance between load demand and power supplied. At this point the turbine gates will stop moving, due to the restoring effect on the pilot valve 34. The action so far described is the first 80 phase and is known as the primary restoration. It will be appreciated that at the end of this primary restoration, the turbine gates are in the correct position to prevent further increase in speed but the speed of 85 the unit is higher than normal and in order to bring this speed back to normal, the secondary restoration must take effect. This is produced in the following manner.

When the restoring rod 27 rises, due to 90 gate movement as already explained, the dash pot 19 prevents movement of one end of the short lever 15, and consequently the other end of lever 15 rises and compresses the spring 23. This spring tends to return 95 to its original position and thus exerts a force on the piston in the dash pot which will slowly move to its new position, the rate of motion depending on the setting of the by-pass valve 145. The downward movement 100 of the rod 22 results in a corresponding downward movement of the end 14 of the long lever 12 which causes an upward movement of the other end of lever 12 and a corresponding upward movement of pilot 105 valve 34 and the main valve 35. This slight additional movement of the main valve 35 results in a further closing movement of the turbine gates and thus brings the speed of 110 the unit back to normal. This secondary restoration is however a slow movement in order to bring the speed back to normal without the danger of oscillating below and above normal.

It will be noted that the connection 46 between the link 20 and the short lever 15, is 115 adjustable by means of the thumb screw 47 and if this adjustment is such that connection 46 lies directly in line with connection 14, the governor will so operate as to give 120 constant speed of the turbine irrespective of the load on the machine. This is due to the fact that after both the primary and secondary restoration have taken full effect, connections 46 and 14 have returned to exactly 125 the same position and the other end of 130

lever 12 which is attached to the pilot valve has also returned to its original position, and hence the center of lever 12 which is connected to the collar 11, must be in its 5 original position which can only correspond to one speed of rotation. In ordinary operation, it is desirable however that the speed of the main unit shall decrease slightly from no load to full load, particularly in order 10 that the various governors in the plant may properly divide load changes. This change in speed is termed inherent speed drop and the governor is adjusted so that the speed of the unit will decrease from 1% to 3% 15 as the load is increased from zero to full load. This is accomplished by so adjusting the thumb screw 47 that connections 14 and 46 will be slightly apart as shown in Fig. 1. With such an ad- 20 justment the elevation of connection 14 will vary slightly for each position of the turbine gates, for it is evident that as the turbine gates close, restoring rod 27 rises, connection 46 always returns to the same po- 25 sition and hence connection 14 will also rise resulting in slightly higher speeds of the turbine as the gates close.

It is usually desirable in power plants to maintain constant speed of the units at all 30 loads, and therefore a means is provided by which the operator can adjust the speed to normal after load changes have occurred in the plant. This adjustment is taken care of by means of the hand wheel 48. This 35 hand wheel is attached to sleeve 24 which in turn is attached to bushing 49, which bushing is keyed to rod 22. Therefore, by revolving the hand wheel 48, the cross head 21 can be raised or lowered in order to ad- 40 just the speed to normal for each load on the unit. This adjustment can also be made by means of the small motor 50, which is usually controlled from the switchboard gallery so that the speed of the unit may be 45 adjusted by means of it from the switch- board gallery.

The revolving element of the govenor is protected by a stationary head 51 which is secured to the governor stand 4. Above the 50 stationary head is mounted a sight feed oil cup 52 which provides lubrication through pipe 53 to the governor collar 11 and also to the thrust and steady bearing 2. The oil after passing through these bearings collects in chamber 54 and is thence drained off through cock 55.

This governor is also provided with a gate limiting device which may be set for any predetermined maximum gate opening 55 desirable on the unit. This gate limiting device consists of a rod 94 (Fig. 1) connected to a boss on restoring lever 29, so that this rod 94 moves in synchronism with the turbine gates. To this rod is attached a screw section 95 which drives a lever 96. As

the turbine gates open, lever 96 is revolved in a clockwise direction until the face 97 of the lever comes in contact with rod 98 which rod is directly connected to the main governor valve 35. Therefore, for a given set 70 of lever 96, when the gates have arrived at their predetermined position, lever 96 prevents any further opening of the main governor valve 35 and hence prevents any further opening of the turbine gates. The 75 position of lever 96 may be varied by means of the adjusting rod 99. A scale 100 is provided at a convenient point on this rod so that the maximum gate opening desired may readily be set. This gate limiting device 80 therefor operates directly on the main governor valve 35 and has no effect whatsoever on the pilot valve 34, the lever 12 or the fly-weights 6. In former designs of governors it has been necessary to provide springs in 85 connection with the pilot valve rod, in order to permit further movement of the fly-weights after the gate limiting device has prevented further movement of the pilot valve rod. In the present design of gov- 90 ernor it is noted that the gate limiting device acts directly on the main governor valve 35 and therefore free movement of the pilot valve 34 and its connections to the fly-weights is permitted without danger of 95 opening the turbine gates a further amount.

In connection with the above mechanism providing for the automatic regulation of the gate opening according to the load it is also often desirable to provide hand control of the gate mechanism to take care of the starting up of the unit and periods during which the automatic mechanism is disabled. This hand mechanism is shown most clearly in diagrammatic form in Fig. 3 100 which also shows in outline the automatic mechanism and its connection to the turbine gate operating means and the hand control. The main pipes which connect the 105 governor valve to the operating cylinder at the turbine and to the pressure supply and return tanks are also shown diagrammatically in Fig. 3. The fluid under pressure enters through pipe 57 and passes to the center chamber 36 (Fig. 1) of the main governor valve. Pipe 44 connects chamber 42 of the main governor valve to the closing side of the operating cylinder 69. Pipe 56 connects chamber 45 of the main governor valve to the opening side of the operating cylinder 69. Pipe 58 connects the exhaust 110 chambers 41 of the main governor valve to the sump or return tank from which the governor pumps draw their supply. In 115 order to shut off the governor, pressure operated plunger valves 72 are provided in the governor valve casing 73. It is usual to provide three of these plunger valves for shutting off flow through pipes 44, 56 and 57, as 120 it is usually not considered necessary to pro- 125 130

vide a valve for the exhaust pipe 58. These plunger valves are all operated simultaneously in the following manner:

To close the valves, fluid pressure is admitted in chamber 74 to the top of all three valves and pressure is exhausted from the annular chamber 75 of all three valves. This causes the plunger valves to close against the seat rings 76 and thus prevents flow of the fluid between the main governor valve 73 and the operating cylinder 69. These three valves 72 are operated by means of the lever 77 and the four way plug cock 65. By referring to Fig. 3, if the lever 77 is moved to the position indicated in full lines for hand control operation, the plug cock 65 is so rotated as to introduce fluid pressure on the top of the plunger valves 72 from pipe 57 through the pipes 59, 63 and 62. At the same time, such setting of the plug cock 65 relieves the pressure from the annular chamber 75 of the plunger valves through pipes 61, 60, 64 to 58. With such a setting therefore of the plug cock, all of the plunger valves 72 move simultaneously to the closed position and so shut off the main governor operation. When lever 77 is moved to dotted line position 78 for governor operation, conditions are reversed so that the plunger valves 72 are all moved by fluid pressure to their open position and the governor is in operation.

The hand control valve is located in pedestal 79 Fig. 2. The valve proper 80, controls the flow of the pressure fluid to the operating cylinder 69. The hand control valve 80 as shown in Fig. 2 and diagrammatically in Fig. 3 is in its central position so that the valve covers the ports in the valve chamber 81 and thus prevents any flow. When lever 77 (Fig. 3) is set on the hand control position the pressure from pipe 57 is connected by pipe 59, plug cock 65, and pipe 63, to the central chamber 82 of the hand control valve. The hand control valve 80 is operated by means of the hand wheel 181. This hand wheel rotates shaft 182 which is provided with a threaded portion 183 (Fig. 4) so that when the hand control is in operation, the clutch 184 is raised or lowered by means of hand wheel 181. Clutch 184 is connected to one end of lever 85 (see Fig. 2) which is pivoted at point 86 and connected at its other end with rod 87, which directly controls the hand control valve 80. In Fig. 3 which shows the arrangement diagrammatically, clutch 184 is shown directly connected to shaft 187. When the unit is on hand control, the lever 77 is in such a position that clutch 184 is thrown in. In this position the clutch jaws 185 (Fig. 3) which are attached to clutch 184 are in mesh with screw thread 183. Fig. 4 shows the clutch thrown out of gear

which is the position used when the unit is on governor operation.

When the unit is being operated on hand control, a movement of the hand wheel 181 to raise the valve 80 results in pressure being admitted from central chamber 82 through pipe 88 and pipe 44 to the closing side of the operating cylinder 69, and at the same time permits the exhaust of the fluid from the opposite side of operating cylinder 69 through pipes 56 and 89, to chamber 90, and thence through pipe 60, plug cock 65, pipe 64, and pipe 58 to the sump tank. When the hand wheel 181 is turned in the opposite direction the valve 80 is lowered and the flows are reversed so that the operating cylinder opens the turbine gates.

In order to properly control the unit when on hand control, a restoring mechanism is provided so that for each movement of valve 80 through hand wheel 181, there is a corresponding restoring movement of valve 80 in order to stop the gates moving. By this means the motion of the turbine gates is in exact proportion to the movement of the hand wheel 181. This restoring mechanism is shown in Fig. 3 diagrammatically, and shows the connection between the operating cylinder rod 70, through lever 91 to rod 182. In the actual construction of the governor as shown in Figs. 1 and 2, the restoring connection from the operating cylinder rod 70 is made to the lever 29 which is mounted on the operating shaft 30. This shaft is connected to rod 182 by lever 92 so that as the turbine gates move, the restoring mechanism will return the valve 80 to its central position through the movement of rod 182, clutch 184, lever 85 and rod 87.

When the hand control lever 77 is moved to the position of governor control 78, the hand control valve is cut out by means of the plug cock 65 and the pressure in pipe 60 is prevented from operating on the hand control valve 81 by means of the check valve 67. When lever 78 is in position for governing operation, clutch 184 is thrown out so that the jaws 185 are no longer in contact with screw thread 183 as shown in Fig. 4. When in this position rod 182 is disconnected from clutch 184 so that the movements of rod 182, due to gate movements of the turbine, are not transmitted to lever 85 or the hand control valve 80. Under such conditions lever 85 is held in its central position by means of the springs 93 which are attached to the governor base 31. It is seen from this arrangement that when the unit is operating on governor control, the hand control valve 80 is always held in its central position and is not affected by any movement of the turbine gates, due to governing action.

At any time when it is desirable to change

the unit from governor to hand control, this may be accomplished by merely throwing over lever 77 from position 78 to full line position, which simultaneously accomplishes 5 the three requirements namely: Shutting off the governor entirely by closing the three plunger valves 72, admitting pressure to the hand control valve 81, and throwing clutch 184 into mesh. This operation is accomplished in a fraction of a second and 10 without any danger of moving the turbine gates from their position before the change was made. In other types of governors this result cannot be accomplished for the hand control is separate and it is always necessary to set the hand control valve at the particular gate opening at which the unit is operating on governor, before the change over is made. In the present governor however, 15 this is not necessary as the hand control valve is always held in its central position and the change over from governor to hand control can be made instantly without any previous adjustment being necessary.

25 In the governor of this invention the entire interconnecting mechanism of the automatic and hand control is mounted on a single base. The main governor pedestal is at the center with the valve mechanism and hand control on surrounding pedestals standing on the same base. The shift lever 77 and hand wheel 181 are conveniently located together and all the operating parts are easily accessible for inspection and repair. With 30 this simplicity of operation is combined ruggedness of structure and delicacy and accuracy of operation. Though the automatic and hand controls are instantaneously interchangeable by the throwing of a single lever yet each when in operation is entirely independent of the other. The automatic control is left wholly free to float to positions as determined by the turbine speed and the positions taken by the regulating gates.

45 I claim:

1. In a governor mechanism for hydraulic turbines the combination with a supporting base separate from the turbine and spaced therefrom, of a governor pedestal on said 50 base comprising a governor head, and additional pedestals for hand control mechanism and auxiliary equipment separately supported on said base.

2. In regulating mechanism for hydraulic turbines the combination with power operated means for controlling the flow, automatic governing means and hand control means for controlling the supply of power to said power operated means, restoring 55 mechanism for said automatic governing means and hand control means, and means for correlating the movements of said automatic and hand control means so that they are interchangeable without preliminary adjustment of either.

3. In regulating mechanism for hydraulic turbines the combination with power operated means for controlling the flow, automatic governing means and hand control means for controlling the supply of power 70 to said power operated means, restoring mechanism for said automatic governing means and hand control means, and means for correlating the movements of said automatic and hand control means so that they are instantaneously interchangeable without preliminary adjustment of either.

4. In regulating mechanism for hydraulic turbines the combination with power operated means for controlling the flow, automatic governing means and hand control means for controlling the supply of power 80 to said power operated means, restoring mechanism for said automatic governing means and hand control means, and means for correlating the movements of said automatic and hand control means so that they are interchangeable by a movement of a single member without preliminary adjustment 85 of either.

5. In a governing mechanism for a hydraulic turbine, the combination with automatic governing means comprising governor valve mechanism, of hand control means comprising hand operated valve mechanism 95 and restoring mechanism therefor, and shift means for closing or opening the governor valve mechanism and simultaneously connecting and disconnecting said hand operated valve mechanism.

6. In a governor mechanism for a hydraulic turbine, the combination with gate operating means, of automatic governing means comprising governor valve mechanism, hand control means comprising hand operated valve mechanism and restoring mechanism therefor, and shift means for closing or opening the governor valve mechanism and simultaneously connecting or disconnecting said hand operated valve mechanism with or from said gate operating means.

7. In a governor mechanism for a hydraulic turbine, the combination with gate operating means and restoring mechanism, 115 of automatic governing means comprising governor valve mechanism, hand control means comprising hand operated valve mechanism, and shift means for closing or opening the governor valve mechanism and simultaneously connecting and disconnecting said hand operated valve mechanism with or from said gate operating means and restoring mechanism.

8. In a governor mechanism for hydraulic turbines, the combination with a hand control valve and gate mechanism of means for operating said valve comprising a hand wheel, and means for restoring said valve to central position by movement of said gate 125 127

- mechanism so as to move the hand control valve into position to stop the movement of the turbine gates until further movement of said hand wheel.
5. 9. In a governor mechanism for hydraulic turbines the combination with a hand control valve and gate mechanism, of means for operating said valve comprising a hand wheel and intermediate clutch, and means 70 for restoring said valve to central position by movement of said gate mechanism so as to move the hand control valve into position to stop the movement of the turbine gates until further movement of said hand wheel.
10. 10. A governor mechanism for hydraulic turbines having a hand control valve and automatic control equipment mounted in twin vertical pedestals supported on a base 75 plate which also supports the governor stand.
11. 11. In a governor for hydraulic turbines the combination of a long floating lever and a short floating lever, of a dash pot connected to one end of the short floating lever and having an adjustable by-pass attached to the piston of the dash pot so as to vary the time 80 of stroke of this dash pot and thus permit the secondary compensation to act in the most efficient manner.
12. 12. In a governor for hydraulic turbines the combination of a long floating lever and a short floating lever, of a restoring rod connecting an intermediate point of the 85 short floating lever to a lever located within the governor base and linked to the piston of the main operating cylinder of the turbine gates.
13. 13. In a governor for hydraulic turbines 40 a gate limiting device in which an element mechanically moved by the turbine gates is brought in contact with an element moved by fluid pressure.
14. 14. In a governor for hydraulic turbines 45 a gate limiting device acting on the main governor valve so that when the turbine gates arrive at a predetermined maximum opening, further opening movements of the gates are prevented by mechanically preventing any further opening movement of the main governor valve.
15. 15. In a governor for hydraulic turbines 50 a gate limiting device consisting of levers and links, located in the governor base plate, and driven from the restoring mechanism connected directly to the turbine gates, these levers and links being so arranged that for a given setting, one of the levers will come in direct contact with a projection on the 55 bottom of the main governor valve and thus prevent further opening movements of this valve.
16. 16. In a governor mechanism for a turbine 60 a plurality of governing means each having restoring mechanism and means for 65 shifting from one to the other of said governing means.
17. 17. In a governor mechanism for a turbine a plurality of governing means each having a restoring mechanism and means for shifting from one to the other of said governing means, said last means comprising restoring mechanism connecting and disconnecting means. 70
18. 18. In a turbine governing mechanism, a 75 restoring mechanism, comprising restoring and restored elements and a clutch connected to one of said elements and adapted to release the other of said elements for independent movement and to grip said other element so as to connect and disconnect said elements at any desired point in the operation. 80
19. 19. In a turbine governing mechanism operating means, a pair of governing means 85 acting alternatively to control the supply of power to said operating means and comprising restoring mechanism, and means for shifting from one to the other of said governing means, said last means comprising 90 a device for rendering said restoring mechanism inoperative.
20. 20. In a regulating system for hydraulic turbines automatic regulating means and remote operated means constructed and arranged to regulate said turbine to the exclusion of said automatic means, each of said means comprising restoring mechanism. 95
21. 21. In a governing mechanism for turbines automatic governing means controlling 100 the supply of power to the turbine gate operating means and hand control governing means controlling the supply of power to the turbine gate operating mechanism comprising restoring mechanism, and means for shifting from one to the other of said governing means.
22. 22. In a governing mechanism for turbines automatic governing means controlling 110 the supply of power to the turbine gate operating means and remote hand control governing means controlling the supply of power to the turbine gate operating means and comprising restoring mechanism, and means for shifting from one to the other of 115 said governing means.
23. 23. The combination of a turbine governing means, a member movable from an initial position to control said means, a connection between said means and member 120 for returning said member to its initial position, other means for controlling said turbine governing means and a device arranged to break said connection and render said other means available to control said governing means. 125
24. 24. In a regulating system for hydraulic turbines a controlling valve comprising co-operating parts both of which are movable, a controlling means for one of said parts, 130

- and means for limiting the movement of the other of said parts.
25. In a regulating system for hydraulic turbines a controlling device comprising co-operating contacting parts both of which are movable to control said turbine, fly weights connected to one of said parts for moving the same and separate means for limiting the movement of the other of said parts.
- 10 26. In a regulating system for hydraulic turbines a controlling valve comprising co-operating parts both of which are movable to control said turbine, fly weights connected to one of said parts for moving the same and gate limiting means for controlling the movement of the other of said parts.
- 15 27. In a turbine gate operating mechanism, controlling means therefor and an adjustable means movable with said gate operating mechanism for limiting the operation of said controlling means so as to limit the extent of movement of the gates.
- 20 28. In a turbine, gate operating mechanism, controlling means therefor comprising fly weights, a valve member movable thereby and a controlling piston movable in response to the movement of said valve member and a gate limiting device comprising a movable stop for said piston.
- 25 29. In a governing mechanism for turbines, fly weights and a controlling valve member moved thereby, operative connections between said member and the turbine
- gates and other means cooperating with said connections to limit the movement of said gates without limiting the movement of said valve member.
30. In a controlling means for hydraulic turbines a base, a plurality of pedestals mounted upon said base, controlling devices carried by said pedestals and operative connections for said devices extending through said pedestals and base.
31. In a controlling means for hydraulic turbines a base, a plurality of pedestals mounted upon said base, controlling devices carried by said pedestals and operative connections between said devices extending through said pedestals and base.
32. In a controlling means for hydraulic turbines a base, a plurality of pedestals mounted upon said base controlling valves carried by said pedestals and fluid and mechanical operative connections between said devices extending through said pedestals and base.
33. In a turbine gate operating mechanism, a valve for controlling said mechanism, a pilot valve for controlling the operation of said first named valve, said pilot valve comprising cooperating parts both of which are movable, speed responsive mechanism for controlling one of said parts and gate limiting means for limiting the movement of the other of said parts.

FRANK H. ROGERS.
